UNITED STATES PATENT OFFICE

166,830

REVERSIBLE TABLE BASE OR SIMILAR
ARTICLE

Charles C. Shinn, Greenbelt, Md., assignor of
one-fourth to Miles D. Pillars, Washington,
D. C.

Application June 27, 1950, Serial No. 10,780

Term of patent 14 years

(Cl. D33—14)

To all whom it may concern:

Be it known that I, Charles C. Shinn, a citizen of the United States, residing at Greenbelt, Prince Georges County, in the State of Maryland, have invented a new, original, and ornamental Design for a Reversible Table Base or Similar Article, of which the following is a specification, reference being had to the accompanying drawing, forming part thereof.

In the drawings:

Figure 1 is a perspective view of a reversible table base showing my new design located in one of its positions;

Figure 2 is a front view of the table base positioned as shown in Figure 1;

Figure 3 is a left hand end view of the table base positioned as shown in Figure 1;

Figure 4 is a right hand end view of the table base positioned as shown in Figure 1;

Figure 5 is a perspective view of the table base showing my new design wherein the table base is reversed and located in an inverted position from that shown in Figure 1;

Figure 6 is a front view of the table base positioned as shown in Figure 5;

Figure 7 is a left hand end view of the table base positioned as shown in Figure 5; and

Figure 8 is a right hand end view of the table base positioned as shown in Figure 5,

The dotted line showing of the table top in Figures 1 and 5 of the drawings is for illustrative purposes only.

I claim:

The ornamental design for a reversible table base or similar article, as shown and described.

CHARLES C. SHINN.
